(57) **CLAIM**

The ornamental design for a rotational screwdriver handle, as shown and described.

DESCRIPTION

FIG. 1 is a top-front-right perspective view of a rotational screwdriver handle showing my new design;

FIG. 2 is a bottom-rear-left perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines in FIG. 1-8 are for the purpose of illustrating portions of the rotational screwdriver handle which form no part of the claimed design.
